US0D1027557S

(12) **United States Design Patent** (10) **Patent No.:** **US D1,027,557 S**
(45) **Date of Patent:** **** May 21, 2024**

(54) **CONTAINER**

- (71) Applicant: **Runway Blue, LLC**, Alpine, UT (US)
(72) Inventors: **David O. Meyers**, Layton, UT (US);
John R. Omdahl, II, Lindon, UT (US)
(73) Assignee: **Runway Blue, LLC**, Alpine, UT (US)
(**) Term: **15 Years**
(21) Appl. No.: **29/869,373**
(22) Filed: **Dec. 29, 2022**

Related U.S. Application Data

- (63) Continuation of application No. 29/760,741, filed on Dec. 3, 2020, now Pat. No. Des. 974,116.
(51) **LOC (14) Cl.** **07-01**
(52) **U.S. Cl.** **D7/510; D9/435**

(57) **CLAIM**

The ornamental design for a container, as shown and described.

DESCRIPTION

FIG. 1 is a top front isometric view of a container showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top front isometric view thereof in an environment in which it may be used.

The dashed broken lines in the figures show portions of the container or environment that form no part of the claimed design. The dot-dash broken lines in the figures and the areas within the dot-dash broken lines show portions of the container that form no part of the claimed design.

1 Claim, 8 Drawing Sheets
